UNITED STATES PATENT OFFICE.

JAMES CARROLL, OF NEW YORK, N. Y.

DESIGN FOR A PUZZLE BOX OR CASE.

SPECIFICATION forming part of Design No. 27,363, dated July 13, 1897.

Application filed May 21, 1897. Serial No. 637,603. Term of patent 7 years.

To all whom it may concern:

Be it known that I, JAMES CARROLL, a citizen of the United States, residing at New York, in the county of New York and State of New York, have invented and produced a new and original Design for Puzzle Boxes or Cases, of which the following is a specification, reference being had to the accompanying drawings, forming a part thereof.

10 In the drawings forming part of this specification, Figure 1 is a plan view of a puzzle box or case, showing my new and original design; and Fig. 2, a section thereof on the line 22, these two views being deemed necessary 15 to fully illustrate my design.

In the drawings forming part of this specification the separate parts of my design are designated by the same numerals of reference in each of the views, and the principal features of my design consist in a rectangular box or case composed of a bottom 5, side walls 6, and end walls 7, and said box or case is provided at each corner with a chamber 8, which is formed by the end and side walls of 25 the box or case, and inwardly-directed short

vertical walls or flanges 9, with which are connected diagonal inwardly-directed walls or flanges 10, whereby narrow passages 11 are formed which lead from the chambers 8 in the direction of the center of the box or casing and which terminate at equal distances therefrom, and centrally of the bottom of the box or casing is a circular chamber 12, formed by a circular vertical wall or flange 13, in one side of which is an opening or passage 14. 30

My newly-designed puzzle box or case and the various parts thereof are symmetrical and regular in form.

Having fully described the same, I claim as new and desire to secure by Letters Patent— 40

The design for a puzzle box or case herein shown and described.

In testimony that I claim the foregoing as my invention I have signed my name, in presence of the subscribing witnesses, this 20th 45 day of May, 1897.

JAMES CARROLL.
